(57) **CLAIM**

The ornamental design for a syringe cap as shown and described.

DESCRIPTION

FIG. 1 is a top perspective view of a first embodiment of a syringe cap shown in a position for use;

FIG. 2 is another top perspective view thereof;

FIG. 3 is a bottom perspective view thereof;

FIG. 4 is a right-side view thereof;

FIG. 5 is a left-side view thereof;

FIG. 6 is a top view thereof;

FIG. 7 is a bottom view thereof;

FIG. 8 is a top perspective view of a second embodiment of the syringe cap;

FIG. 9 is a bottom perspective view thereof;

FIG. 10 is a right-side view thereof;

FIG. 11 is a left-side view thereof;

FIG. 12 is a top view thereof; and,

FIG. 13 is a bottom view thereof.

In the drawing figures, features shown in broken lines indicate portions that form no part of the claimed design.

1 Claim, 3 Drawing Sheets
